UNITED STATES PATENT OFFICE

GLENN V. JEFFERSON AND EDWIN G. LITTLE, OF WILKINSBURG, PENNSYLVANIA,
ASSIGNORS TO THE UNION SWITCH & SIGNAL COMPANY, OF SWISSVALE, PENNSYLVANIA, A CORPORATION OF PENNSYLVANIA

RAILWAY SWITCH OPERATING APPARATUS

Application filed January 5, 1932. Serial No. 584,818.

Our invention relates to railway switch operating apparatus, and particularly to apparatus of the type whereby a track switch may be optionally operated either by a power device or by a manually operable lever.

One object of our invention is the provision, in apparatus of the type described, of novel and improved means for locking the apparatus against manual operation by unauthorized persons.

We will describe two forms of apparatus embodying our invention, and will then point out the novel features thereof in claims.

In the accompanying drawings, Fig. 1 is a top plan view of a switch machine provided with locking apparatus embodying our invention. Fig. 2 is a side view of the apparatus shown in Fig. 1. Fig. 3 is a sectional view taken on the line III-III of Fig. 2. Fig. 4 is a sectional view taken on the line IV-IV of Fig. 2. Fig. 5 is a detail view of hand-throw lever B forming part of the apparatus shown in Fig. 1. Fig. 6 is a front elevational view of the plate member 1 forming part of the apparatus shown in Fig. 1. Fig. 7 is a front elevational view showing a modified form of our invention.

Similar reference characters refer to similar parts in each of the several views.

Referring first to Fig. 1, the reference characters A and B designate two levers which, as here shown, are the selector and hand-throw levers, respectively, of a railway switch machine of the type whereby a switch may be operated either by hand or by power means. These levers are mounted for rotation about a common axis, and each may be rotated from the extreme position shown through an angle of approximately 220° to another extreme position. Our present invention relates solely to a means for locking the levers in certain predetermined positions, as will be explained more fully hereinafter, and it is in no way concerned with the mechanism of the switch machine. Accordingly, it is believed that a detailed description of the mechanism of the switch machine would be superfluous, and that a full understanding of our present invention will be had from the following brief

description of the general operation of the switch machine.

When the selector lever A occupies the extreme position in which it is shown in the drawings, the track switch is disconnected from the hand-throw lever and is connected with a suitable power device, not shown, such for example, as an electric or fluid pressure motor. If, however, the selector lever A is rotated from the extreme position shown to its other extreme position, the track switch will then become disconnected from the power device and will become connected with the hand-throw lever B. Under these latter conditions, the switch may be reversed at the will of the operator by operating the hand-throw lever from one extreme position to the other.

The locking means embodying our invention includes a plate member 1 which is located between a hub 4 formed on the selector lever A and a hub 6 formed on the hand-throw lever B, and which plate member is fastened at its lower end to a bracket 2 secured to the side of the switch machine. The plate member 1 has formed in one side thereof a recess 3 which receives the hub 4 of the selector lever, and in the other side thereof a recess 5 which receives the hub 6 of the hand-throw lever. Extending through the plate member 1 between the hubs 4 and 6 is a hole 7 (see Figs. 4 and 6) in which a steel ball 8 having a diameter which is somewhat larger than the length of the hole 7 is loosely mounted. When the selector and hand-throw levers occupy the extreme positions in which they are shown in the drawings, the hub 4 of the selector lever engages the steel ball 8 and forces it part way into a recess 10 formed in the hub 6 of the hand-throw lever, thus locking the hand-throw lever against any movement whatsoever under these conditions. Similarly, when the selector lever occupies the extreme position shown and the hand-throw lever occupies its opposite extreme position, the hub 4 of the selector lever again engages the steel ball 8 and forces it into another recess 11 in the hub 6 of the hand-throw lever to lock the hand-throw lever against movement in this ex-

treme position. If, however, the selector lever is rotated from the extreme position shown to its opposite extreme position, a recess 12, formed in the hub 4 of the selector lever, will then be in alignment with the steel ball 8, and under these latter conditions, the hand-throw lever can be operated, the steel ball 8 being forced into the recess 12 and out of the recess 10 or 11, depending upon which extreme position the hand-throw lever initially occupied.

The locking means embodying our invention also comprises a locking dog 13 which as best seen in Fig. 3 is pivotally supported on a pin 14 carried by two latterly extending arms 15 formed on the bracket 2. The dog 13 is biased by gravity to rotate in a counter-clockwise direction, and is adapted to cooperate at its inner end with a notch 16 in the plate member 1 (see Figs. 3 and 6). The dog 13 is also adapted to cooperate with a notch 17 (see Fig. 2) in the periphery of the hub 4 of the selector lever, and with two angularly spaced notches 18 and 19 (see Fig. 5) in the periphery of the hub 6 of the hand-throw lever. The notch 17 is V-shaped, and is so positioned that this notch will align with the notch 16 in the plate member 1 when and only when the selector lever occupies the extreme position shown in the drawings. The notches 18 and 19 are so positioned that these notches will align respectively with the notch 16 in the plate member 1 according as the hand-throw lever occupies the extreme position in which it is shown in the drawings or its opposite extreme position.

It will be apparent from an inspection of the drawings that when the notches 16, 17 and 18 are all in alignment, as is the case when the selector and hand-throw levers both occupy the extreme positions shown, the dog 13 will automatically enter these notches due to its bias. Similarly, when the notches 16, 17 and 19 are all in alignment, as is the case when the selector lever occupies the extreme position shown, and the hand-throw lever occupies its opposite extreme position, the dog will then automatically enter these notches. If, under either of the above conditions, a locking device, such for example as a padlock 20, is placed in an eye 21 formed in the upper part of the outer end of the dog as shown in Fig. 3, the padlock will engage the under side of the arms 15 and will prevent clockwise rotation of the dog, and it follows that both levers will then be locked against movement by the dog. If, however, the padlock 20 is removed from the eye 21, the dog 13 will then be free to rotate clockwise, and if the selector lever A is then rotated from the extreme position shown, the dog, due to the shape of the notch 17 in the selector lever, will be automatically moved out of engagement with all of the notches which it previously occupied and will sub-

sequently be held out of engagement with the notches until the selector lever is returned to the extreme position shown and the hand-throw lever is rotated to one or the other of its extreme positions. When the dog is out of engagement with the notches, the hand-throw lever is unlocked so far as the dog is concerned, and if the selector lever then occupies the position for hand operation, that is to say, the opposite extreme position from that in which it is shown in the drawings, the hand-throw lever may be operated from one extreme position to the other to reverse the switch at the will of the operator, as previously described.

The extreme positions of the selector lever are limited by means of two adjustable stop screws 22^a and 22^b which are screwed into lugs 24 and 23, respectively, formed on the bottom of the plate member 1. The stop screws 22 are each locked in their adjusted positions by means of a lock nut 25. The extreme positions of the hand-throw lever are determined by two stop members 26 and 27 secured to the side of the switch machine.

In Fig. 7 we have shown our invention applied to a switch machine of the type described and claimed in an application for Letters Patent of the United States, Serial No. 557,335, filed by Edwin G. Little on August 15, 1931. Referring to Fig. 7, the reference character B1 designates a hand-throw lever, and the reference character C designates a foot pedal, which hand-throw lever and foot pedal correspond, respectively, to the hand-throw lever 26 and foot pedal 51 in the said Little application. The hand-throw lever B1 is rotatable from the position in which it is illustrated in the drawings through an angle of approximately 220°, and the foot pedal C is biased to the position in which it is illustrated in full lines in the drawings by suitable means not shown, but may be depressed to the position in which it is shown in dotted lines. The operation of the switch machine is fully described in the said Little application, and for a clear understanding of our present invention, the operation need be only briefly outlined.

When the hand-throw lever B1 occupies either extreme position and the foot pedal C occupies the position in which it is shown in full lines in the drawings, the switch is disconnected from the hand-throw lever and is connected with a suitable power device not shown. If, however, the hand-throw lever is rotated from either extreme position through an angle of approximately 20°, which rotation is usually termed a "preliminary" movement of the lever, the switch will become disconnected from the power device, and if the position of the switch and the hand-throw lever then correspond, the switch will become connected with the lever. If the position of the switch and hand-throw lever do not cor-

respond at the completion of either preliminary movement of the lever, the switch will remain disconnected from the lever until the lever is rotated to a position corresponding to the position of the switch. When the switch is connected with the hand-throw lever, the switch may be reversed at the will of the operator by rotating the lever B1 between the positions at which the two preliminary movements terminate, this movement of the lever being referred to as the "main" movement. In order to disconnect the switch from the hand-throw lever after it has been connected with the lever, and to again connect it with the power device, the hand-throw lever B1 is rotated to one end or the other of the main part of its movement and the foot pedal C is depressed. The depression of the foot pedal C disconnects the lever from the switch and connects the switch with the power device, and the lever may then be moved to its adjacent extreme position.

Formed in the hub 35 of the hand-throw lever B1 are three notches 28, 29 and 30, which are adapted to cooperate with a locking dog 31 formed on the foot pedal C. The locking dog 31 is so proportioned and the location of the notches 28 and 30 are such that, if the foot pedal is permitted to move to its full line position under the action of its bias when the hand-throw lever occupies the extreme position shown or its opposite extreme position, the dog 31 will enter the notch 30 or the notch 28 as the case may be. Under either of these conditions, if the padlock 20 is inserted in an eye 32 located in an extension 33 formed on the foot pedal C, the padlock will cooperate with a lug 34 formed on the case of the switch machine to prevent the foot pedal from being depressed sufficiently to withdraw the dog 31 from either of the notches 28 or 30, thus locking the hand-throw lever against movement. If, however, the padlock 20 is removed from the eye 32, and the foot pedal is depressed just far enough to withdraw the dog from the associated notch, the hand-throw lever may then be rotated in the manner previously described. The parts are so proportioned that the movement of the foot pedal necessary to unlock the hand-throw lever will have no effect on the remainder of the switch operating apparatus. If the foot pedal C is released after the hand-throw lever has been rotated from either extreme position through the preliminary part of its movement, the locking dog 31 will then enter the notch 29. When the dog is within this notch, the ends of the notch act as stops to limit the main part of the movement of the lever to the desired amount.

Although we have herein shown and described only two forms of railway switch operating apparatus embodying our invention, it is understood that various changes

and modifications may be made therein within the scope of the appended claims without departing from the spirit and scope of our invention.

Having thus described our invention, what we claim is:

1. In combination, two levers each rotatable between two extreme positions, one of said levers being provided with two spaced notches, a dog adapted to enter one or the other of said notches according as said one lever occupies one or the other of its extreme positions when said other lever occupies its one extreme position, a padlock, and means including said padlock for at times preventing withdrawal of said dog from said notch.

2. In combination, a first lever rotatable between two extreme positions and provided with two spaced notches, a second lever rotatable between two extreme positions and provided with a single notch, a dog biased to a position in which said dog will enter the notch in said second lever and one or the other of the notches in said first lever according as said first lever occupies one or the other of its extreme positions when said second lever occupies its one but not its other extreme position, and means for at times preventing withdrawal of said dog from said notches.

3. In combination, a first lever rotatable between two extreme positions and provided with two spaced notches, a second lever rotatable between two extreme positions and provided with a single notch, a dog biased to a position in which said dog will enter the notch in said second lever and one or the other of the notches in said first lever according as said first lever occupies one or the other of its extreme positions when said second lever occupies its one but not its other extreme position, and a single instrumentality for at times preventing withdrawal of said dog from said notches.

4. In combination, a first lever rotatable between two extreme positions and provided with two spaced notches, a second lever rotatable between two extreme positions and provided with a single notch, a dog biased to a position in which said dog will enter the notch in said second lever and one or the other of the notches in said first lever according as said first lever occupies one or the other of its extreme positions when said second lever occupies its one but not its other extreme position, a padlock, and means including said padlock for at times preventing withdrawal of said dog from said notches.

5. In combination, a first lever rotatable between two extreme positions and provided in its hub with two spaced notches, a second lever rotatable between two extreme positions and provided in its hub with a single notch, a fixed plate member between the

hubs of said levers and provided with a notch, the notches in said first lever being so disposed that one or the other of these notches will align with the notch in said plate member according as said first lever occupies one extreme position or the other and the notch in said second lever being so disposed that this notch will align with the notch in said plate member when and only when said second lever occupies one of its extreme positions, a dog biased to a position in which the dog will enter the one notch in said first lever, the notch in said plate member and the notch in said second lever when these notches are all in alignment, or the other notch in said first lever, the notch in said plate member and the notch in said second lever when these notches are all in alignment; and means cooperating with said dog for at times locking said dog in the position in which the dog is in one group or the other of said notches to lock both levers against movement.

6. In combination, a lever rotatable between two extreme positions and provided with a notch, a foot pedal movable between a first position and a second position, a locking dog secured to said foot pedal in such manner that when said foot pedal occupies its first position said dog will enter the notch in said lever if and only if said lever occupies a predetermined one of said extreme positions, and means for at times locking said foot pedal in the position in which said dog enters said notch to lock said lever against movement.

7. In combination, a lever rotatable between two extreme positions and provided with two spaced notches, a foot pedal movable between a first position and a second position, a locking dog secured to said foot pedal in such manner that said locking dog will enter one or the other of said notches according as said lever occupies one or the other of its extreme positions when said foot pedal occupies its first position, an extension on said lever provided with an eye, a padlock adapted to be at times inserted into said eye, and means effective when said padlock is within said eye for locking said foot pedal in its first position.

In testimony whereof we affix our signatures.

GLENN V. JEFFERSON.
EDWIN G. LITTLE.
